(57) **CLAIM**

The ornamental design for a tailgate surface, as shown and described.

DESCRIPTION

FIG. 1 is a rear left elevated perspective view showing a first embodiment of our new design, the broken line showing being for illustrative purposes only, and forms no part of the claimed design.

FIG. 2 is a front left elevated perspective view showing a right front elevated perspective view of the tailgate surface design shown in FIG. 1.

FIG. 3 is a plan view of the tailgate surface design of FIG. 1.

FIG. 4 is a front view of the tailgate surface design of FIG. 1.

FIG. 5 is a rear view of the tailgate surface design of FIG. 1.

FIG. 6 is a left side view of the tailgate surface design of FIG. 1.

FIG. 7 is a right side view of the tailgate surface design of FIG. 1.

FIG. 8 is a bottom view of the tailgate surface design of FIG. 1.

FIG. 9 is a rear left elevated perspective view showing a second embodiment of our new design, the broken line showing being for illustrative purposes only, and forms no part of the claimed design.

FIG. 10 is a front left elevated perspective view showing a right front elevated perspective view of the tailgate surface design shown in FIG. 9.

FIG. 11 is a plan view of the tailgate surface design of FIG. 9.

FIG. 12 is a front view of the tailgate surface design of FIG. 9.

FIG. 13 is a rear view of the tailgate surface design of FIG. 9.
